UNITED STATES PATENT OFFICE.

JUAN F. GRICE, OF IDAHO FALLS, IDAHO.

ROOFING AND FASTENER.

Application filed April 21, 1926. Serial No. 103,588.

- My present invention has reference to composition roofing and a means for clamping the edges of the overlapping roofing strips or shingles to the underlying strips in a manner which will effectively hold the strips in proper contacting engagement so that they cannot be influenced by wind, or other weather conditions to permit of the entrance of air or moisture therebetween.
- 10 A further object is to simplify and cheapen the construction of composition roofings either of the roll or shingle type by glazing or sanding only the exposed portions of such roofings.
- 15 To the attainment of the foregoing the invention consists in the improvement as hereinafter described and definitely claimed.
- In the drawings:
- Figure 1 is a plan view of a shingle roofing in accordance with this invention.
- 20 Figure 2 is a sectional view on the line 2—2 of Figure 1.
- Figure 3 is a sectional view on the line 3—3 of Figure 1.
- 25 Figure 4 is a sectional view on the line 4—4 of Figure 1.
- Figure 5 is a perspective view of one of the clamps employed.
- 30 Figure 6 is a plan view of a blank from which the clamp is constructed.
- Figure 7 is a fragmentary plan view of a roll or strip roofing in accordance with this invention.
- 35 Figure 8 is a sectional view on the line 8—8 of Figure 7.
- Figure 9 is a view illustrating a slightly modified form of clamp.
- 40 In Figures 1 to 4, the roofing is composed of shingles 1. Each of the shingles has its outer edge formed with a reduced extension 2, the edges of said extensions being arranged at angles in the usual manner. These edges and a portion of the shingles inward of the edges are sanded, glazed or otherwise treated with a preservative, as at 3. The outer edges at the confronting edges of the shingles 1 are notched, as at 4, and the tongues 2, adjacent to their outer edges are each provided with substantially rectangular slots 5. The shingles are tacked on the roof at points adjacent to the outer corners of the body thereof, as indicated by the numeral 6. The shingles, of course, are laid in rows in
- the usual manner, and are disposed in lapping relation whereby one row of shingles 55 is attached to the underlying row by the element 6.
- To hold the extending tongue portions of the shingle in tight contacting engagement so that the same cannot move away from each other by the influence of wind or other weather conditions, and thereby preserve a water-tight joint between the over and underlying shingles, I provide locking means of a simple but novel construction. The locks, or more strictly speaking, the clamps are each constructed from a blank of thin metal as disclosed by Figure 6 of the drawings. The clamp may be and preferably is of tin or other cheap bendable material. 65 Each clamp comprises a substantially rectangular body portion 7 that has its inner corners beveled outwardly as at 8, its inner end from its said corners inclined toward the center thereof and the said center formed with a V-shaped finger 9. The body at points a suitable distance from the finger 9 and to the opposite side of the said finger is slotted longitudinally and from thence transversely, and the metal bounded by these slits provides a tongue 10. The body has its outer end cut at opposite inclinations to points adjacent the center thereof, and the edges of the body, from points opposite the tongue to the said inclined outer edges 11, 70 are widened, and these widened portions are designed to be bent upwardly to provide flanges 12.
- 75 After the flanges are formed on the body the same is inserted between the lapping shingles at the meeting edges thereof, so that the tongue 10 will be disposed in the notch 4. The tongue 10 is bent and extended through the opening 5, and the outer end of the body is then bent over the outer edge of the extension 3 so that the tongue 10 is received through the slot 14 provided by the referred to slotted portions of the body at the opposite sides of the tongue. The tongue is then further bent over the outer end of the body, which for distinction is indicated by the numeral 15, and the said end 15 is compressed against the shingle so that its flanges 12 will be forced into the overlying extension 3 of the said shingle. In this manner it will be noted that I have provided an effective lock-

ing means for tightly clamping the overlying ends of the shingles to the underlying shingles in a simple manner which will prevent the entrance of moisture between the 5 shingles or the said shingles being influenced by wind or other weather conditions.

In Figures 7 and 8, I have illustrated a roll of sheet roofing. In this instance the overlying strip 16 is provided, adjacent to 10 its outer edge, at spaced intervals, with a rectangular opening 17 and the clamp is inserted between the overlying and underlying sheets in a line with the said slots 17. Preferably the finger 9 is bent downwardly 15 and inserted in the underlying sheet 18, and also, if desired, a nail or other securing means 19 may be passed through the body for more effectively holding the same on the underlying sheet 18. The tongue of the 20 clamp member 7 is bent and extended through the opening 17, and the portion 15 of the said body is then bent over the outer edge of the sheet 16 so that the tongue is received through the opening 14 and bent 25 over the body in a manner as previously described. In this instance the tongue and the end 15 of the body are also subjected to a force of contact such as a blow from a hammer so that the flanges or biting elements 12 30 will enter the overlying sheet 16.

In Figure 9 the clamp is similar to that previously described except that the finger 9 is omitted. This cheapens the manufacture of the clamp or fastener.

The roofing shingles have notches at the corners of their meeting ends, and the inner edge of each of the shingles is formed with a V-shaped notch 50. By such arrangement the shingles may be reversed and the 35 clamps applied thereto as heretofore described. The V-shaped notches 50 provide a guide line for the convenience of laying the shingles so that the said shingles may be kept in proper alignment. While I have 40 stated that only the exposed portion of the shingles is glazed, sanded or treated with minerals, this only applies when the shingles are arranged as disclosed by Figures 1 and 7 of the drawings, and when the shingles 45 are to be reversed the entire outer surface of the said shingles is treated as above described.

The simplicity and advantages of the improvement will, it is thought be apparent, 55 and while I have illustrated a satisfactory embodiment of the improvement, my features of invention are capable of extended application and I do not wish to be limited to the specific structure herein shown and 60 described.

Having described the invention, I claim:

1. A composition roofing, laid in overlapping courses, the outer roofing courses, adjacent to the edges thereof having spaced 65 openings therethrough, means for clamping

the overlying to the underlying courses, comprising a body of bendable material, having a tongue designed to be bent and passed through the mentioned openings, and also adapted to have its outer end bent over the 70 edge of the overlying roofing and having an opening therethrough to receive the tongue, which latter is then bent against the outer fold of the said body.

2. A composition roofing, laid in overlapping 75 courses, the outer roofing courses, adjacent to the edges thereof having spaced openings therethrough, means for clamping the overlying to the underlying courses, comprising a body of bendable material, having a tongue designed to be bent and passed 80 through the mentioned openings, and also adapted to have its outer end bent over the edge of the overlying roofing and having an opening therethrough to receive the tongue, which latter is then bent against the outer fold of the said body and said outer fold having its edges formed with flanges which 85 enter the outer roofing course.

3. The combination, roofing shingles arranged in lapping courses and having their 90 meeting edges, at their outer ends, notched and formed, inward of the notches, with extensions provided with openings adjacent to the outer ends thereof, and the said openings, in the outer course of shingles, adapted 95 to lie in the notches in the underlying course of shingles, means for clamping the edges of the overlying shingles to the underlying shingles, comprising each a thin 100 bendable metal plate having its inner end centrally formed with a bendable finger and the body thereof provided with a rectangular opening and with a bendable tongue which is arranged centrally in the opening, 105 said body outward of the tongue and opening having its edges flanged, said tongue designed to be bent and passed through the notches and the opening in the respective under and overlying shingles, and the outer 110 portion of the body adapted to be bent over the edges of the overlying shingle to receive the tongue through the opening thereof, and the latter bent over this end of the body and the said end compressed against 115 the extension of the overlying shingles to force the flanges thereon into said extension.

4. A clamp for the purpose set forth, formed from a bendable strip of thin metal, comprising a substantially rectangular body 120 having its inner corners widened, and its inner edge cut inwardly toward the center thereof and the said center formed with an outstanding bendable substantially V-shaped finger, said body having a central opening 125 therethrough and a bendable tongue arranged in the opening, the body, outward of the opening in the tongue, having its edges widened and the said edges bent to provide flanges, as and for the purpose set forth. 130

5. A clamp for the purpose set forth, formed from a bendable strip of thin metal, comprising a substantially rectangular body which has outwardly extending corner projections at one of its ends, its body centrally provided with a tongue which is bendable in either direction with respect to

the body and said body outward of the tongue, having its edges formed with upstanding flanges which terminate away from 10 the second end of the body.

In testimony whereof I affix my signature.

JUAN F. GRICE.
